Patent expires April 23, 1966

3 Claims. (Cl. 200—52)

1

In certain working machines in the textile industry there is a requirement for feeling by means of an electrical contact acting directly on the goods undergoing treatment in the machine. Thus in flat cards, combers, drawing frames etc., in which the goods leave the machine as a loose sliver, it is required that a feeling contact disconnects the driving motor, if for some reason the sliver should burst.

In strenters and similar machines, the loose cloth is fed in spread condition into the machine between two endless chains provided with clips or pins which hold the cloth. In that part of the machine, where the cloth is fed in, the chains are arranged in turnable arms, so that the distance between the chains successively increases and in such a manner the cloth is stretched out to normal width before it is fed into the drying chamber, whereafter the chains run parallel. Each arm is arranged at the feeding end on a screw spindle, which is operated by an electric motor through a reversing switch and a feeder control switch consisting of a contact apparatus, which is operable by means of a feeler pressing against the selvedge of the cloth and automatically, through the motor, adjusts the arm into such a position that the edge of the cloth is caught by the clips or pins.

In all the cases described above the pressure which the feeling member of the feeder control, i. e. the feeler, can be allowed to exert on the goods is so little that a satisfactory contact pressure cannot be obtained. Further it is desirable in strenters and the like that the margin of obliquity of the selvedge of the cloth is entirely utilized so that the number of adjusting impulses is reduced as far as possible. The operating intensity of the feeder control switches of a strenter often amount to about 1000 times per hour or more which demands very much of the motor and the operating member. In order to solve this problem the feeder control, according to the present invention, is made so that a permanent magnet operating the contact apparatus and turnable by means of the feeler is inserted between the contact apparatus and the feeler. By this means the adjusting power of the contact apparatus will be independent of the power with which the feeler is pressed on to the goods and its range of insensibility, which is the turning angle described by the magnet in order to operate the contact apparatus, can be easily adjusted with regard to the margin of obliquity of the cloth.

The invention will now be described with reference to the accompanying drawings, in which,

2

Figure 1 is a perspective view, showing the principal design of the feeder control, and

Figure 2 is a plan view of one of the contacts as seen from above in Figure 1.

Referring to the drawings the feeder control consists of a shaft 1 which is turnably journaled in a frame 2. One end of the shaft 1 carries a feeler 3 which by means of a spring 4 is held pressed against the edge of the cloth 5 which is moving in the direction of the arrow. On the other end of the shaft 1 there is a circular permanent disc magnet 6, the peripheral surface of which is provided with a groove 7. The edges 8 of the disc on either side of the groove 7 form the poles of the magnet. Over a certain part of its circumference the diameter of the disc is reduced. In Figure 1 the upper part of the disc has a smaller diameter than the lower part. The places where the disc passes from large to small diameter have the designations 9, 10.

In the form of the invention shown in Figure 1 two contact apparatuses are arranged on each side of the magnet. Each contact apparatus consists of a fixed contact 11 and a movable contact 12 which is pressed against the fixed contact by means of a spring 13. The spring 13 is provided with a soft iron armature 14 which is attracted by the disc magnet when the larger diameter of the latter is before it, with the result that contacts 11, 12 are opened. When the smaller diameter of the disc magnet, however, is before the armature, the force of the spring 13 predominates and the contacts 11, 12 are closed.

In order to prevent the armature 14 from touching the disc magnet and hindering its movement, the armature is provided with a stop which is more clearly shown in Figure 2. The movable contact is formed with a contact head 12 and a smaller part 15, which is connected with the spring 13. Between the contact head 12 and the spring 13 a fixed stop 16 is arranged. The smaller part 15 of the movable contact passes through a hole 17 in this stop. When the armature 14 is attracted by the disc magnet 6, the motion of the movable contact is limited by the back part of the contact head 12 coming into contact with the stop 16 which is so arranged that there is always an air gap between the armature 14 and the edges 8 of the disc magnet.

In Fig. 1, the parts 9, 10 between large and small diameter of the disc magnet 6 are before the armatures 14. In this position the contacts 11, 12 on the two contact apparatuses are opened. If the cloth 5 does not run evenly but moves an angle α_1 to the left, the feeler 3 follows this move-

ment. The shaft 1 and the disc magnet 6 are thus also turned through the same angle, so that the smaller diameter of the magnet comes before the armature 14 of the contact arrangement to the right, the contacts of which are closed, as the spring force of the spring 13 in this position predominates. Hereby the driving motor of the regulating arrangement of the cloth is started in such a direction that the cloth is carried to the right until the feeler 3, the shaft 1 and the magnet 6 are turned back to their original positions in which the armature 14 of the right contact arrangement is again attracted and its contacts 11, 12 are opened, so stopping the regulating arrangement of the cloth.

If the cloth moves an angle α_2 to the right, the same procedure is repeated with the difference, that it is now the left contact apparatus which is actuated and which starts the driving motor of the regulating arrangement of the cloth in such a direction that the cloth is carried to the left until its mean position is reached once more.

The angle α , by which the feeler is moved to one side or the other forms the margin of obliquity, within which the cloth is allowed to move sideways. When the places 9, 10 are before the armature, as shown in Figure 1, the margin of obliquity is a minimum, as only a very small angular movement of the feeler is required to cause the contact apparatuses to make regulating impulses to one side or the other.

The margin of obliquity can be increased by moving the two contact apparatuses against each other around the disc magnet, so that the latter must move through a larger angle before the places 9, 10 pass the respective armatures 14. Referring to Figure 1, this is effected by turning the adjusting screw 18 in the direction of the arrow, which causes the bridge 19, and trunnions 20, 21 fixed thereto, to be pressed downwards. The trunnions 20, 21 in their turn press on their respective sheaves 22, 23 which are turnably journaled on the bushing 24, which is fixed to the frame 2 and also serves as bearing for the shaft 1. The turning angle of the sheaves is limited by the size of the notch 25 in the sheaves and the stop bolt 26 fixed into the frame 2. The movement of the bridge 19 is limited by the stop bolts 27 which are also fixed to the frame 2. The sheaves are turned in opposite directions with

the shaft 1 as turning centre and a spring 28 is arranged to exert the required counter-pressure. As the right contact apparatus is fixed on the sheave 22 and the left one on the sheave 23, the two contact apparatuses will thus turn against each other with the same turning centre as the magnet 6. The farther the armatures of the contact apparatuses are adjusted away from the places 9, 10 over the portion of larger diameter of the magnet, the larger the range of insensitivity of the apparatus will be, which means a larger margin of obliquity for the cloth, which easily can be adjusted to the suitable value.

I claim as my invention:

15. 1. Operating mechanism for an electrically driven textile machine, having means for controlling the lateral position of goods traveling through the machine, comprising a feeler directly feeling the traveling goods, a permanent magnet turned by said feeler, said permanent magnet forming a circular disc having a part reduced in diameter and a groove all around the circumference of the disc, an armature for the magnet, a contact device, a spring moving the contact device in one direction, said device being operated by the armature against the action of said spring when attracted by the said magnet when the latter is turned by said feeler so that that part of the magnet having the larger diameter is before the armature, and a stop device preventing the armature from touching the magnet.
20. 2. Operating means according to claim 1 comprising means for turning the contact device about the axis of the permanent magnet.
25. 3. Operating mechanism according to claim 1, comprising a pair of said contact devices, and means whereby such devices are turned with equal angular movements in opposite directions about the axis of the permanent magnet.
